UNITED STATES PATENT OFFICE.

CHARLES W. STONE AND HENRY M. HOBART, OF SCHENECTADY, NEW YORK,
ASSIGNORS TO GENERAL ELECTRIC COMPANY, A CORPORATION OF NEW
YORK.

ELECTRICITY TRANSFORMING AND CONVERTING APPARATUS.

1,337,100.

Specification of Letters Patent. Patented Apr. 13, 1920.

Application filed September 6, 1916. Serial No. 118,635.

To all whom it may concern:

Be it known that we, CHARLES W. STONE and HENRY M. HOBART, citizens of the United States, residing at Schenectady, county of Schenectady, and State of New York, have invented certain new and useful Improvements in Electricity Transforming and Converting Apparatus, of which the following is a specification.

10 Our invention relates to electricity transforming and converting apparatus, that is to say, to apparatus for performing the double function of transforming alternating current electricity from one voltage to another and of converting one form of electric energy to energy of a different characteristic. More specifically, our invention relates to electrical machines for receiving high pressure polyphase alternating current electricity from a supply system and delivering relatively low pressure direct current electricity to a distribution system.

The transformation and conversion of high pressure alternating current electricity to low pressure direct current electricity is now usually accomplished by stationary step-down transformers and synchronous converters. The stationary transformers step-down the high pressure electricity to voltages suitable for the synchronous converters, and the latter machines receive the low pressure alternating current electricity through suitable slip rings and deliver correspondingly low pressure direct current electricity at suitable commutator brushes. It is a well known fact that the alternating current voltage impressed upon the alternating current side of a synchronous converter bears a direct relation to the direct current voltage. The direct current voltage is determined by the character of the load with which the machine is to be used, and, in consequence, the alternating current voltage of the converter is almost invariably different than the voltage of the supply circuit, which necessitates the installation of some form of transforming device between the supply circuit and the converter. Accordingly, as above stated, it has been the common practice in the past to use transformers. In city sub-stations almost universally air-blast type transformers have been used. In rural stations both air-blast and oil, and oil

and water cooled transformers have been used.

In many cases the installation of transformers of any type requires a considerable expenditure of money, and such transformers occupy considerable valuable space. The electrical connections from the transformers to the synchronous converters are also costly and liable to cause trouble. Some of these objections to the use of transformers have forced operating companies to use motor-generator sets, winding the stator of the alternating current machine for the line potential. Motor-generator sets are more costly and far less efficient than synchronous converters with transformers, hence a natural result for engineers to endeavor to achieve has been to devise a machine which was some compromise between the synchronous converter and motor-generator set. This endeavor has resulted in the development of the motor converter, which we will not attempt to discuss herein, except to point out that the motor converter is a compromise on the higher frequencies, as it is somewhat less expensive than a motor-generator set and somewhat more efficient, but is less efficient and more costly than a synchronous converter for the same work.

The principal object of our present invention is to provide an improved electricity transforming and converting apparatus. In this connection our invention aims broadly to provide a novel and improved form of apparatus for performing the double functions of transforming alternating current electricity from one voltage to another and of converting alternating current energy into energy of different characteristics. The particular object of our present invention is to provide an improved apparatus for receiving high pressure polyphase alternating current electricity from a supply system and delivering relatively low pressure direct current electricity to a distribution system. Other objects of the invention will be brought out hereinafter.

In carrying out the objects of our present invention, we provide an electricity transforming and converting apparatus comprising essentially a rotatable transformer in combination with suitable electricity converting means of the rotary type, such as a

dynamo-electric machine, for converting alternating current electric energy into energy of different characteristics, such for example as direct current energy, and in certain instances mechanical energy. The transformer is electrically connected to the electricity converting means, and in accordance with our present invention is mounted on the same shaft as the rotatable member of the converting means. Where the apparatus is employed for receiving high pressure polyphase alternating current electricity and delivering relatively low pressure direct current electricity, and vice versa, the electricity converting means is preferably of the synchronous converter type having an armature winding rotatably mounted within the influence of a stationary magnetic field system. The transformer is then mounted on the same shaft as the armature core of the synchronous converter, and the transformer and armature windings thus rotate as a single mechanical unit. The magnetic cores of the armature and transformer windings may be independent and arranged side by side on the rotatable shaft, or these two cores may be combined into a single core, as for example by slotting the interior of the armature core for the accommodation of the transformer windings. The primary winding of the transformer is electrically connected to suitable electric current collecting means, such for example as slip rings carried on the rotatable shaft. The secondary winding of the transformer is electrically connected to the armature winding of the dynamo-electric machine, and one of the particular advantages of our present arrangement is that the secondary winding can be tapped into the armature winding of the converter at a greater number of places per pair of poles of the latter than is practicable in the case of any existing apparatus with which we are familiar. Briefly, the principal advantages of our improved apparatus are that all of the high efficiency and low cost of the synchronous converter are retained, all of the high efficiency of the transformer is retained, and the transformer can be wound for the ordinary line potentials commonly used, without the necessity of the installation of separate transformers and the leads thereto, thus making our apparatus a self-contained unit of high efficiency, low cost and excellent operating characteristics. In our improved apparatus, the synchronous converter becomes a better operating machine, besides being of lower cost, due to the multiplicity of phases, whereby the hot spots in the armature winding of the synchronous converter are substantially eliminated. The transformer, due to the fact that it is rotated, can be more efficiently cooled than any form of stationary transformer, thus

making it possible to build a transformer occupying considerably less space than heretofore. These and other advantages of our improved apparatus will be brought out and discussed in greater detail hereinafter.

70

The novel features of the invention which we believe to be patentably characteristic thereof are definitely set forth in the appended claims. The invention itself and the construction and mode of operation of apparatus embodying the invention will be better understood from the following descriptions and discussions taken in conjunction with the accompanying drawings in which:

80

Figure 1 is a diagrammatic elevation of an electricity transforming and converting apparatus embodying our present invention; Fig. 2 is a diagram of the electrical connections of the apparatus of Fig. 1; Figs. 3 and 4 are diagrams of modified connections of certain of the windings of the apparatus; Figs. 5, 6, 7 and 8 are detail views showing a practical construction of the transformer employed in our improved apparatus; Figs. 9 to 19, inclusive, are diagrammatic views of various arrangements we have found particularly advantageous for obtaining a multiplication of phases in our improved apparatus; Fig. 20 is a diagrammatic view of 90 a transformer designed to produce a multiplication of phases particularly adapted for use in our improved apparatus; Figs. 21 and 22 are diagrams of the electrical connections of the primary and secondary 100 windings, respectively, of the transformer of Fig. 20; Figs. 23 and 25 are practical winding diagrams of phase-multiplying transformers embodying the broad principle of phase-multiplication of the transformer 105 of Fig. 20; and Figs. 24 and 26 are detail views of the slotted laminations of the magnetic cores of the transformers represented in Figs. 23 and 25, respectively.

The general construction and principle of 110 operation of the machine of our present invention will be most readily comprehended by reference to Figs. 1 and 2 of the accompanying drawings. The machine is mounted on a suitable base 30. Bearing posts or pillar blocks 31 are suitably secured to the base and provide the bearings for the rotatable shaft 32 of the machine. It will be observed that the shaft 32 has only two bearings, one at each end. The shaft 32 carries a step-down transformer T and the rotor of a dynamo-electric machine R. High tension alternating current electricity is fed from the three-phase supply mains 33 to the primary winding 34 of the transformer T by 120 means of slip rings 35 and co-operating brushes 36. The slip rings 35 are so proportioned as to carry the high pressure current absorbed by the machine at its rated load. Machines of the character for which our in- 130

vention is particularly designed are now usually required for operation from circuits with pressures between 5,000 and 12,000 volts, and, since at these pressures the current for a given power is very much smaller than for pressures of 150 to 600 volts, such as heretofore employed for the slip rings of a synchronous converter fed by stationary transformers, the amount of space and the weight and cost of material devoted to the slip rings is relatively very small. The brushes by means of which the current is conducted to the slip rings 35 are omitted in Fig. 1, but are diagrammatically indicated in Fig. 2, and the rigging by which the brushes are carried has been omitted in both figures in order to simplify the drawings. It will of course be understood that the brushes and brush-rigging may be of any accepted design suitable for machines of this general type.

The slip rings 35 are electrically connected to the terminals of the primary winding 34 of the transformer T. While we have illustrated a single transformer T, it is to be understood that two or more transformers may be mounted on the shaft 32 if desired. The preferred construction of the transformer or transformers T will be described in detail hereinafter. In the embodiment of our invention illustrated in Fig. 2 the primary winding 34 consists in effect of two three-phase windings one of which is delta-connected and the other star-connected, and the two three-phase primary windings are preferably connected together and to the slip rings as indicated. In the arrangement of Fig. 2 it will be noted that the delta-connected three-phase transformer constitutes in effect the neutral of the star-connected three-phase transformer. The star-connected three-phase transformer may have its terminals connected to the terminals of the delta-connected three-phase transformer, as diagrammatically represented in Fig. 3 of the drawings, and in some cases this arrangement will be preferable to that represented in Fig. 2.

The secondary winding 37 of the transformer T has two separate coils for each coil of the primary winding. The secondary winding thus has twelve coils which may be arranged to form a closed ring or mesh winding, as diagrammatically represented in Fig. 2. If desired the twelve secondary coils may be connected to form a twelve-phase star, as diagrammatically represented in Fig. 4. Whether mesh or star-connected the twelve terminals of the secondary winding are similarly connected to appropriate points of the armature or rotor winding 38 of the dynamo-electric machine R. The machine R is in substance a synchronous converter, and the armature winding 38 is thus similar to the armature winding of the

usual synchronous converter, and is, accordingly, connected to the segments of a commutator 39. The armature winding 38 is surrounded by a stationary field winding 40 adapted to be supplied with direct current energy from the brushes 41 bearing on the commutator 39. The direct current mains are also connected to the brushes 41, as will be well understood by those skilled in the art. The field winding 40 has such a number of poles as to produce the desired speed of rotation of the rotor of our improved machine, as will also be clearly understood by those skilled in the art.

Before proceeding further with the detailed description of the construction of the improved machine of our present invention, it is desirable at this point to contrast the general arrangement illustrated in Figs. 1 and 2 with the arrangement heretofore, and now, usual in the art, which consists of a synchronous converter, such as that whose armature, commutator and field are represented at 38, 39, and 40, respectively, of Figs. 1 and 2, but which is, in addition, provided with a member of large slip rings connected into appropriate parts of the armature winding. Through brushes bearing upon these slip rings, current is supplied to the synchronous converter from stationary transformers. In such an outfit, the voltage at the slip rings must bear a definite relation to the desired commutator voltage. Since the latter is usually of the order of 220 to 700 volts, the pressure at the collector rings must also be of similar low values. In such sets as are used by the large electricity supply companies in cities, the current which has to enter this synchronous converter at each ring often runs into many thousands of amperes. Six slip rings are usually employed, and when each has to carry several thousand amperes it is obvious that the space occupied by and the weight and cost of the slip rings may run to formidable proportions.

When the space occupied on the shaft by such low pressure slip rings is replaced by a step-down transformer and three high pressure slip rings, as illustrated in Fig. 1 of the accompanying drawings, although the shaft has to be of slightly larger diameter to carry the increased weight of the transformer, the length of the shaft between bearings is but little greater than in the usual synchronous converter supplied by stationary transformers. Furthermore, the space in the sub-station occupied by the step-down transformers in the heretofore, and now usual, arrangement is saved in our improved outfit, and when such sub-stations are located in cities where land is expensive this saving of floor space is of much importance. Heretofore, the stationary transformers have usually been of the type in which

the active material, comprising iron, copper, and insulation, is immersed in large tanks of oil, in which are also immersed coils through which water is circulated to maintain the oil cool and to thus dissipate the losses in the transformer. In large cities the outlay for the water required for such cooling purposes is an item which represents an appreciable proportion of the total costs of operation of a sub-station. As an alternative, transformers are sometimes employed of a type which are kept cool by the forced circulation through them of air, supplied by a blower which is in turn driven by a motor.

15 In the improved machine of our present invention the transformer is mounted on a rotating shaft, and no transformer plant of either of the types just described is required.

It has already been mentioned that the 20 synchronous converter now usual in the art is customarily provided with six slip rings. Formerly, only three slip rings were employed, and this leads us to a consideration of a very important property of synchronous converters, namely,—that they are in several respects improved the greater number of taps through which the alternating current electricity is sent into the armature winding. When only three slip rings are

30 provided, there can be but three taps per pair of poles. With the present usual practice of providing six slip rings, there are six taps per pair of poles. It has been proposed that twelve slip rings should be provided.

35 This would permit of twelve taps per pair of poles, but no such departure has been made in commercial machines, it having been considered that the multiplicity of slip rings, each with its brushes and brush-rigging, would introduce complications not justified by the improvement which would thereby be effected in the synchronous converter. However this may be, it will be observed that by mounting the step-down

40 transformer on the rotating shaft of a synchronous converter, it becomes practicable to supply alternating current electricity to the armature of the converter through a large number of taps per pair of poles and without encountering any of the embarrassments mentioned, since the low pressure electricity is not carried to the synchronous converter through slip rings. The advantages of employing large numbers of taps in the armature winding of the synchronous converter per pair of poles will be more particularly mentioned hereinafter.

45 The mechanical and electrical design of the step-down transformer T carried on the 50 rotatable shaft 32 will be understood by reference to Figs. 5, 6, 7 and 8 of the accompanying drawings. The magnetic core of the transformer consists of two main sections 43 and 44. The core-section 43 is made up in the usual manner of star-shaped

punchings of laminated magnetic material, and when the primary and secondary windings have been properly assembled on the six legs or spokes of this section, the other core-section 44, which is made up of annular laminations, is forced over the outer circular periphery of the six legs of the star-shaped section. The two sections of the magnetic core are securely held together by insulated splines 45. The laminations 70 of the core-section 43 are held together by two sets of insulated bolts 46 and 47, the latter set of bolts extending through annular end plates 48 at each end of this section of the magnetic core. The core-section 44 is 75 held together by a set of insulated bolts 49 which extend through the radial flanges of two hollow cylindrical end plates 50 and 51. The end plates 50 and 51 form 80 housings at each end of the magnetic core for the transformer windings and connections, as will be seen by reference to Fig. 6, and as will be more fully described hereinafter. The insulation of the splines 45 and of the bolts 46, 47 and 49 consists of a surrounding layer or sheath of insulating material, as will be clearly seen by reference to Figs. 6 and 8 of the drawings.

One coil of the primary winding and two coils of the secondary winding are 95 wound on each leg of the star-shaped core-section 43. As previously mentioned, these coils are assembled before the annular core-section 44 is added. The two coils of the secondary winding 37 are first assembled 100 on the legs of the core-section 43 and the four terminals of these coils are suitably connected to the terminals of the other coils and to twelve terminal rings 52, in accordance with the desired scheme of connection, 105 as for example diagrammatically represented in Fig. 2 or in Fig. 4 of the drawings. The terminal rings 52 are flat rings arranged in two concentrically disposed groups of six each. Each terminal ring is 110 carefully insulated from the adjacent ring, as clearly shown in Fig. 6 of the drawings. The terminal rings 52 are connected to the appropriate points of the armature winding 38 by means of radially disposed conductor strips 53, secured to the rings, and horizontally disposed conductor strips 54 (Fig. 1) connecting the outer ends of the strips 53 to the armature winding. It will be understood by those skilled in the art 115 that there will be twelve conductor strips 53—54 per pair of poles of the dynamo-electric machine R, and in Figs. 1, 5, and 6 of the drawings the transformer connections illustrated are designed for a six-pole 120 machine R. In Fig. 2 of the drawings, the dynamo-electric machine R is diagrammatically represented as a two-pole machine, but it will be understood by those skilled 125 in the art that when the machine has a 130

greater number of poles, each pair of poles of the armature winding will in effect be similarly connected in parallel to the terminals of the secondary winding 37 of the 5 transformer T.

The coils of the primary winding 34 are assembled over the coils of the secondary winding 37, as shown in Figs. 6, 7, and 8 of the drawings. The primary coils may be 10 of a more or less triangular cross-section in order to utilize to advantage the openings in the magnetic core of the transformer. The three slip rings 35 are carried on the outer periphery of the cylindrical end plate 51 and are insulated from 15 each other and from the end plate, as clearly illustrated in Fig. 6. Conductors 55 suitably connect the coils of the primary winding 34 to the slip rings 35 and to each other, 20 in accordance with the desired scheme of connection, as for example as diagrammatically represented in Fig. 2 or Fig. 3.

It is now in order to call attention in 25 greater detail than heretofore to the nature of the advantages obtained by employing large numbers of taps per pair of poles. In the following table the total armature I^2R loss in a synchronous converter with six taps per pair of poles is taken as 1.00, 30 and there are shown in the table for twelve and twenty-four taps per pair of poles, the relative I^2R losses in the armature windings for five different power factors:—

35 Number of taps from secondaries of transformer into the armature winding of a synchronous converter per pair of poles.	Relative total I^2R loss in armature winding, that in a machine with six taps per pair of poles being taken as 1.00.				
	Pf=1.00.	Pf=0.99.	Pf=0.94.	Pf=0.85.	Pf=0.75.
6.....	1.00	1.00	1.00	1.00	1.00
12.....	0.76	0.77	0.82	0.85	0.88
24.....	0.70	0.71	0.76	0.80	0.84

45 It will be seen that the gain is greatest at unity power factor, but that it is still very notable even at so low a power factor as 0.75. As a matter of fact, the best practice in the service operation of substations is to maintain the field excitation at such a value that the electricity shall be supplied to the synchronous converter at practically unity power factor. From an examination of the 50 above table, it will be noticed that, while the total I^2R loss in the armature winding is twenty-four per cent. less with twelve taps per pair of poles than with six taps per pair of poles, there is a further gain of only six per cent. in going to twenty-four taps per 55 pair of poles. In this particular respect of the reduction in the total I^2R loss, the greater part of the improvement obtainable by the employment of a greater number of 60 taps per pair of poles is achieved by the use of twelve taps, and it would hardly be

worth while, on this score alone, to employ twenty-four taps, if the latter should be attended by any increased cost or complication. But there are other important respects in which, as we shall now proceed to 70 show, it is well worth while to employ more than twelve taps per pair of poles.

In the armature winding of the synchronous converter the rate of generation of heat is by no means equal in all parts of the 75 copper comprised in the armature winding. Certain conductors, spaced at equal intervals all around the armature, are subjected to much greater heating than those midway between them. The magnitude of this inequality is shown in the following table, in the right hand side of which are given for several power factors, the ratio of the loss per gram of copper at the hottest spots 80 in the armature conductors to the average loss per gram of copper. These figures are given for synchronous converters employing respectively 3, 4, 6, 12 and 24 taps 85 per pair of poles.

Number of taps from secondaries of transformer into the armature winding of the synchronous converter per pair of poles.	Ratio of loss per gram of copper at "hottest spots" in the armature conductors, to average loss per gram of copper.				
	Pf=1.00.	Pf=0.99.	Pf=0.94.	Pf=0.85.	Pf=0.75.
3.....	2.1	2.5	2.8	2.6	2.4
4.....	1.9	2.3	2.6	2.4	2.2
6.....	1.6	1.9	2.2	2.1	1.9
12.....	1.2	1.4	1.6	1.5	1.4
24.....	1.05	1.2	1.3	1.3	1.2

90 As already pointed out, it is the conditions at, or near, unity power factor which are usually of chief importance in the service operation of synchronous converters. Directing our attention to the column for unity power factor, it will be seen that while with three taps per pair of poles, the loss in the "hottest spots" in the armature conductors is over twice as high per gram of copper as is the average loss per gram of copper; when we come to six taps, the ratio is only 1.6; for twelve taps, the ratio is 1.2, and for twenty-four taps, it is only 1.05. In other words, if we employ twenty-four taps per pair of poles, we obtain a close 105 approach to a uniform distribution of heat throughout the armature winding, the greatest variation in the watts per gram 110 of copper only amounting to 5 per cent. above and below the average value. When we realize that this fine result, so far as regards the distribution of heat, is associated, as shown by the table first given, with 115 30 per cent. less total I^2R loss in the armature winding, as compared with a six tap synchronous converter, we are left in no doubt as to the desirability of employing as 120 many as twenty-four taps per pair of poles, 130

provided, of course, that this can be accomplished by simple and inexpensive means.

In the following table are given data which further emphasize the importance of these considerations.

Number of taps from secondaries of transformer into the armature winding of the synchronous converter per pair of poles.	Relative "hottest-spot" loss in armature conductors, that in a machine with 6 taps per pair of poles being taken as 100.				
	Pf=1.00	Pf=0.99	Pf=0.94	Pf=0.85	Pf=0.75
10	100	100	100	100	100
15	58	59	60	64	69
20	47	48	49	52	55

In the right hand side of this table are given for various power factors, values for the relative "hottest-spot" loss in the armature conductors, that in a machine with 6 taps per pair of poles being taken as 100. It will be seen from this table that for unity power factor, the use of twenty-four taps per pair of poles is associated with less than half as great a "hottest-spot" loss as occurs with six taps per pair of poles, and that with even so low a power factor as 0.75, the relative "hottest-spot" loss with twenty-four taps is only 55 per cent. of that with six taps. It has been desirable at this point to introduce the foregoing discussion, since a number of figures to which allusion will next be made, are accompanied with the diagrammatic representation of means for obtaining various numbers of taps per pair of poles by various arrangements of transformer windings.

We have already briefly described the manner in which we obtain twelve taps from the secondary winding of the transformer T. As heretofore explained, these twelve taps are so obtained as to constitute a twelve-phase secondary winding. The primary winding of the transformer consists of a star-connected three-phase winding A-B-C and a delta-connected three-phase winding D-E-F. These two three-phase primary windings may be connected as represented in Figs. 2 or 3. The arrangement of the primary winding represented in Fig. 2 may be preferable to that represented in Fig. 3, since transformers operated in parallel with one another may be subject to trouble through unequal division of the load due to slight inequalities of one sort or another. The two phase-windings or coils of the secondary winding 37 inductively associated with the primary phase-winding A are designated by reference characters a and a' , and the other secondary coils are similarly designated. The secondary coils may be mesh-connected, as represented in Fig. 2, or star-connected, as represented in Fig. 4.

In Figs. 9 and 10 we have diagrammati-

cally illustrated a modified connection of the secondary coils of the transformer T for obtaining twelve taps per pair of poles for the armature winding of the machine R. As in the arrangements hereinbefore described, there are two three-phase primary windings, one delta-connected and the other star-connected to the same slip rings. For the sake of simplicity only the delta-connected three-phase primary winding D-E-F is shown in Fig. 9, and it will be understood that the star-connected three-phase primary winding A-B-C is connected to the slip rings 35 in any suitable manner, as for example as represented in Fig. 13 of the drawings. Each phase-winding or coil of the primary winding has three secondary windings or coils associated therewith. Two of the three secondary coils associated with each primary coil have the same number of turns, while the third secondary coil has twice as many turns as either of the other two secondary coils. In Fig. 10 the legended lines represent the vectors of the corresponding coils of the secondary winding. Thus, in Fig. 10, the vectors d_1 , d_2 and d_3 indicate the arrangement, electrical connection and relation of the corresponding secondary coils d_1 , d_2 , d_3 and so on. The primary phase-winding D is displaced in phase 90 electrical degrees from the primary phase-winding A, as will be evident from an inspection of Figs. 2 and 3, and, accordingly, the secondary coils d_1 , d_2 and d_3 will be displaced in phase by 90 electrical degrees from the secondary coils a_1 , a_2 and a_3 , and so on, as represented by the vectors of Fig. 10. The larger coils a_2 , b_2 , etc., are connected at their middle points to form a common neutral, while the smaller coils a_1 , a_3 , b_1 , b_3 , etc., are connected between appropriate terminals of the larger coils as diagrammatically indicated by the vector diagram of Fig. 10. The corners of the vector diagram of Fig. 10 form the twelve terminals of the resultant twelve-phase secondary winding, and are connected as heretofore explained to appropriate points of the armature winding of the machine R. In Figs. 11 and 12 we have diagrammatically illustrated a simple connection of the secondary winding of the transformer T for obtaining twenty-four taps per pair of poles of the machine R. Here again, two three-phase primary windings are used, but both primary windings are delta-connected, as represented in Fig. 11. The delta-connected three-phase primary windings D-E-F and D'-E'-F' are thus connected in parallel to the slip rings 35. Fig. 12 represents by vectors the arrangement of the secondary coils of the transformer. The vectors are legended to correspond to the secondary coils of Fig. 11, and it will be observed that the secondary coils d_1 and d_2 have fewer turns than the secondary coils d'_1 and d'_2 of

the same phase of the other three-phase transformer. When the secondary coils associated with the two three-phase primary windings have the relative number of turns represented by the lengths of the vectors of Fig. 12 and are arranged as indicated by these vectors, twenty-four taps are obtained and a twenty-four phase secondary winding results in effect. These twenty-four taps 10 are connected to appropriate points of the armature winding of the machine R.

In Figs. 13 and 15 there is diagrammatically represented a modified arrangement for obtaining a twenty-four phase secondary winding of the transformer T. Twenty-four taps per pair of poles are again provided as in the arrangement of Figs. 11 and 12, but each of the cords of the vector diagram of Fig. 15 is of the same length. The 15 arrangement involves the employment of a star-connection of the primary winding A—B—C and a delta-connection of the primary winding D—E—F. The corresponding vector diagram of the six primary windings or coils is represented in Fig. 14, and it will be noted that the winding A is in phase-quadrature with the winding D, and the windings B and C are in phase quadrature with the windings E and F, respectively. 20 Each primary winding or coil has associated therewith two secondary windings or coils, each of the same number of turns. These secondary coils are designated $a_1, a_2, b_1, b_2, C_1, C_2, d_1, d_2, e_1, e_2, f_1$ and f_2 . Thus, we 25 have twelve secondary coils and twenty-four taps, and these coils are arranged as represented by the corresponding vectors of Fig. 15, whereby a substantially twenty-four phase secondary winding is obtained. In 30 order that each secondary coil shall give the same voltage, the relative numbers of turns or amount of magnetic flux in the star-connected primary winding A—B—C and in the delta-connected primary winding D—E—F must be appropriately chosen. Instead 35 of having the delta-connected primary windings in parallel with the star-connected primary windings, they may, with appropriate proportions of turns, or flux, constitute 40 a delta internal to the star-connected primary windings as hereinbefore described. Another arrangement for obtaining a twenty-four phase secondary winding, and hence twenty-four taps per pair of poles of 45 the machine R is diagrammatically represented in Figs. 16 and 17. The primary winding here again consists of two three-phase primary windings, one DD'—EE'—FF' being mesh-connected, and the other 50 AA'—BB'—CC' being star-connected. Each phase winding or coil of the primary winding has six secondary coils associated therewith, of which four (a_1, a_3, a'_1, a'_3) have the same number of turns, while the 55 other two (a_2 and a'_2) have substantially

twice as many turns as each of the other four. The manner in which the secondary coils are interconnected is diagrammatically represented in Fig. 17. The outer circle of coils represents the two three-phase primary windings, but it should be noted that there need not in reality be twelve separate primary windings or coils, since the coils designated A and A' in Fig. 17 may constitute the single coil AA' of Fig. 16. The divided arrangement shown in Fig. 17 is more convenient for indicating the connections of the secondary coils. The larger secondary coils $a_2, a'_2, b_2, b'_2, c_2, c'_2$, etc., have one terminal connected to a common neutral, while the other terminals of these coils constitute twelve taps of the twenty-four phase secondary winding. The intermediate twelve taps of the twenty-four phase winding are formed by connecting in series two of the 80 smaller secondary coils differing in phase by 30 electrical degrees, where one terminal of these series-connected coils is connected to the common neutral and the other terminal constitutes one of the twenty-four terminals 85 of the secondary winding. The vectors of Fig. 17 are legended with the reference characters of the corresponding secondary coils, and the electrical connections and relations of the coils will be obvious to those skilled in the art from the diagram of this figure.

An arrangement of the primary and secondary windings of the transformer T for obtaining thirty-six taps per pair of poles 100 of the machine R is diagrammatically represented in Figs. 18 and 19. The two three-phase primary windings A—B—C and D—E—F are again star- and delta-connected, respectively. Each phase-winding of the primary windings has associated therewith four secondary coils or windings, of which two have a greater number of turns than the others. These secondary coils are designated $a_1, a_2, a_3, a_4, b_1, b_2$, etc., where the coils a_2 and a_4 have the same number of turns and a greater number of turns than the coils a_1 and a_3 . Fig. 19 represents the vectors of the secondary coils shown in Fig. 18, and illustrates the electrical connections 105 and relations of these secondary coils. The vectors are designated by the same reference characters as the corresponding secondary coils, and the connections and arrangements of the coils will be clearly understood from the diagram of Fig. 19, in view of the preceding similar arrangements. It will be evident that thirty-six 110 taps are thus provided, and a thirty-six phase secondary winding is obtained.

Multiplication of the secondary phases may also be obtained by so locating some of the secondary coils in their relation to the magnetic circuits that they experience in various degrees the influence of primary 115

windings of different phases. This is in contrast to the arrangement in which two secondary coils, each exclusively under the influence of primaries of different phases, are connected in series to obtain the intermediate phase.

In Fig. 20 is shown a magnetic system with twelve winding windows in a magnetic core 60. A single primary winding 10 or coil is wound or threaded through each winding window. Thus, there are altogether twelve primary coils legended A, A', B, B', C, C', D, D', E, E', F, and F'. The correspondingly legended primary coils A 15 and A', etc., are connected in series. The series-connected coils A—A', B—B' and C—C' are star-connected, while the series-connected coils D—D', E—E', and F—F' are delta-connected to the three collector 20 rings 35, as diagrammatically represented in Fig. 21. The secondary coils $a, a', b, b', c, c', d, d', e, e', f$ and f' are exclusively under the influence of the correspondingly legended primary coils, whereas the secondary 25 coils $af, fb, bd, bc, ce, ea', a'f', f'b', b'd', d'c', c'e',$ and $e'a$ are under the influence of the two correspondingly legended adjacent primary coils. Thus, the phase of the secondary coil af is the resultant of the 30 phases of the two adjacent primary coils A and F. Thus, there are twenty-four secondary coils from which electricity can be supplied to the synchronous converter R through twenty-four taps per pair of poles. 35 In Fig. 22, the vector diagram of the secondary coils of Fig. 20 diagrammatically indicates a suitable connection of these coils for obtaining twenty-four taps per pair of poles of the machine R. Diametrically 40 opposite, that is correspondingly legended, secondary coils are connected in series with one another, since they are in the same phase, and the centers of these series-connected coils are connected together to form 45 a common neutral.

In Fig. 20, the secondary coil a is shown at the opposite side of the winding window from the primary coil A, but as a matter of fact this would rarely be the case in 50 actual practice, since the secondary coil a would usually be located suitably close to the primary coil A to obtain the necessary minimization of reactance. Indeed, Fig. 20, is to be regarded as merely diagrammatic, 55 and not only the primary coils but the secondary coils could well, in many instances, be suitably subdivided, intermixed and distributed. This distribution may to advantage be in slots similar to the armature slots 60 of a direct current dynamo-electric machine. It would be superfluous to enter upon the possible mechanical space arrangements to which resort may be had in carrying out this principle, but we wish to call attention 65 particularly to two arrangements which

have been found advantageous for a multiplication of the secondary phases in accordance with the principles just outlined.

Fig. 23 is a winding diagram of the primary and secondary windings of a transformer embodying the principle of phase multiplication just described. It will be understood by those skilled in the art that the magnetic core of the transformer resembles the magnetic core of the armature 70 of a direct current dynamo-electric machine and that the coils represented in the winding diagram of Fig. 23 are assembled in suitable slots in this magnetic core, as indicated in the diagram. In the layout of 80 Fig. 23, only three primary slots and twelve secondary slots are employed per pole of the transformer. The transformer has a ten-pole winding and is used in combination with a twenty-pole synchronous converter 85 winding. The figure shows the relative locations of the primary and secondary slots of the various phases. A detail view of one of the laminations of which the magnetic core is composed illustrating the relative arrangement of the primary and secondary slots is shown in Fig. 24. The corresponding part of the winding diagram connecting the secondary winding of the transformer to the armature winding of the synchronous converter lies between M and N of Fig. 23. This portion MN if repeated 90 five times will give the complete diagram. A considerable portion of the complete diagram is shown in Fig. 23. It will be observed that the transformer is located on the other side of the commutator from the side occupied by the armature winding of the synchronous converter. Where this plan is adopted, the connections from the secondary 100 terminals of the transformer are carried straight to the commutator segments. This is the arrangement illustrated in the diagram of Fig. 23. Every fourth commutator segment is shown as indicated at the 105 top of Fig. 23, where the commutator segments are numbered from s^{385} onward to s^{477} and again from s^1 to s^{141} . There are altogether 480 commutator segments and a transformer connection goes straight into 110 each fourth segment. For the case under consideration, namely, a ten-pole transformer and a twenty-pole synchronous converter, this gives good proportions. While criticism would naturally be directed to six 115 different V-shaped connections which are required from the secondary terminals to the commutator segments, it should be pointed out that although these six different shapes are necessary, there will be required ten of 120 each one of these six shapes, and it should be further noted that they are of exceedingly simple construction. In all other respects the connections of the transformer windings are exceedingly simple and reg- 125 130

ular. In designs of these proportions, there will only be a very few, say two or three conductors per secondary slot, and the design could be planned so that these secondary conductors could be thrust through holes from end to end. In the arrangement shown in Fig. 23, there are only twelve secondary phases, but the principle can be developed to provide twenty-four phases. The commutator in the design to which Fig. 23 applies has twenty-four segments per pole, and this would also be an appropriate number for a twenty-four phase design.

Turning to a closer consideration of the transformer, attention should be directed to the four conductor elements, comprising conductors c^1 , c^{14} , c^{26} , and c^{13} . It will be observed that these conductors line up very closely with the A-coil sides of the primary winding. Consequently this elementary group is legended *a*. Consider next the secondary element consisting of conductors c^6 , c^{18} , c^{30} and c^{17} . These line up with the B-coil sides, and this element of the secondary winding is legended *b*. Finally, the secondary element comprising conductors c^3 , c^{22} , c^{34} and c^{21} is legended *c* and lines up with the C-coil sides of the primary winding. Consideration should next be given to the secondary element consisting of conductors c^8 , c^{16} , c^{28} and c^{15} . It will be observed that these conductors lie equally under the influence of coil sides A and B of the primary windings and for this reason this secondary element is legended *ab*. Similar explanation could be made for secondary elements legended *bc* and *ca*, but the idea ought now to be clear from the preceding description.

The above plan amounts to obtaining six secondary phases out of three primary phases and presents certain aspects of difference from the plans described in the earlier portions of this specification. The six secondary phases each have two terminals, so that there are twelve taps per pair of poles. The arrangement thus would usually be called twelve-phase. Obviously, twenty-four phases could be obtained from three phases by an extension of this principle, similarly, 8, 16, etc., phases could be obtained from a quarter-phase supply. In arranging for sixteen phases from a quarter phase supply it might be preferred to have eight primary slots per pole and employ two sets of primary coils, the one set being connected mesh and the other set being connected star.

The many advantages of the improved apparatus of our present invention will be more clearly appreciated by considering a concrete example. For this purpose we have diagrammatically illustrated in Fig. 25 a winding diagram of a 25-cycle outfit capable of delivering 3,500 KW at the commutator at 310 volts and 11,300 amperes. The outfit is, furthermore, capable of giving this same current at any commutator pressure down to 240 volts. For obtaining this voltage regulation at the commutator the usual plan is either to provide a synchronous booster as a component of the apparatus, or else to provide an induction regulator. The dynamo-electric machine of the outfit has twenty poles and is designed for operation at a speed of 150 R. P. M. The transformer carried on the rotatable shaft is designed to step the line pressure of 6,600 volts down to secondary pressures of 200 volts which are tapped in at appropriate places at the end connections of the armature winding of the synchronous converter. Twenty-four taps per pair of poles are employed in the design illustrated in Fig. 25. The slip rings are designed for 6,600 volts, and from them are supplied two primary groups of coils, one group A-B-C being star-connected and the other group D-E-F being delta-connected and the two groups being connected in parallel with one another. Certain advantages, however, accrue to the alternative plan of having these two primary groups of coils in series, that is, having the star-connected coils radiate from the corners of the delta-connected coils. By this latter arrangement faults are overcome which might be quite troublesome where the star-connected and delta-connected coils are connected to the slip rings in parallel. The design under consideration is, however, proportioned with the star and delta windings to be in parallel. The transformer has ten poles and may be regarded as the equivalent of five three-phase transformers, since it has five pairs of poles. There are sixty-primary slots and one hundred and twenty secondary slots. Thirty of the primary slots belong to the star-connected coils while the other thirty slots belong to the delta-connected coils. Each primary slot devoted to the star-connected coils has twenty-eight conductors arranged one wide and twenty-eight deep, while each of the primary slots belonging to the delta-connected coils contains forty-eight conductors. Each secondary slot contains eight conductors arranged four wide and two deep. Each secondary conductor carries 290 amperes. In the star-connected primary circuits, each primary conductor carries 160 amperes. Attention is called to the small amount of current per secondary conductor. The high amount of sub-division of the secondary winding into many parallel circuits is among the many important advantages secured by our invention. The primary I^2R loss is 17,000 watts. The secondary I^2R loss is 23,000 watts. The total copper loss is 40,000 watts. The total iron loss is 36,000 watts. The total of all losses is 76,000 watts, exclusive

of windage, and since the output from the transformer is about 3,700 KW this gives an efficiency at rated load of ninety-eight per cent. The total weight of copper in the 5 transformer is some 6,000 to 7,000 pounds and the total weight of sheet iron is some 40,000 to 50,000 pounds. This should be compared with stationary transformers which have heretofore been furnished in 10 connection with 3,500 KW synchronous converters. In such stationary transformers, the copper weighs about 7,660 pounds and the sheet iron about 27,000 pounds. In accordance with our present invention, however, 15 the outlays for tanks, oil, water, circulation, coils and various other auxiliary features of stationary transformers are eliminated. It should furthermore be remembered that by our invention, the six large 20 collector rings heretofore used on synchronous converters are displaced by three relatively small collector rings. Furthermore, the improvements effected by employing twenty-four phases cheapen the synchronous 25 converter of the outfit and improve the converter itself in several respects, notably in the matters of commutation and uniform temperature distribution.

The winding diagram of Fig. 25 will it is 30 believed be readily understood by those skilled in the art in view of the foregoing explanation. The lower portion of the diagram relates to the six-phase primary winding carried in the sixty slots of the transformer core. The phase-windings or coils of the primary winding are designated A, B, C, D, E, and F, just as in the preceding examples of phase multiplication. The diagram of the secondary winding is shown 35 just above the diagram of the primary winding. The portion of the diagram between the points designated M and N is repeated five times in making up the complete winding diagram. The conductors of the secondary winding of the transformer are leg- 40 ended to indicate the phase-winding of the primary winding under whose influence they lie. Thus, the secondary conductors designated *a* come under the influence of the primary phase-winding A, and the secondary conductors *ad* come under the influence of 45 the primary phase-windings A and D, and so on. Above the diagram of the secondary winding of the transformer are shown the 50 connections whereby the secondary terminals are connected to the appropriate parts of the back end connections of the armature winding of the twenty-pole synchronous converter. It will be seen that there are 55 twenty-four taps per pair of poles of the converter. At the top of Fig. 25 the winding of the synchronous converter and the 60 connections thereof and the commutator segments are generally indicated. The arrangement of the primary and secondary 65

slots of the transformer core will be understood by reference to Fig. 26 which shows a portion of one of the punchings of the core.

The improved electricity transforming 70 and converting apparatus of our present invention is particularly intended to replace the stationary transformers and synchronous rotary converters, and similar apparatus, heretofore used in substations and elsewhere for receiving high pressure alternating current electricity and delivering low pressure direct current electricity. The apparatus has its particular field of usefulness in large and densely settled communities. For such work there has been a rapid increase in the size of synchronous converters. For explanatory purposes we may take the case of a 3,500 KW synchronous converter, having 26 poles, and giving 25 cycles with a speed of 115 R. P. M. 3,500 KW 75 is delivered from the commutator at pressures ranging from 240 to 300 volts. Alternating current electricity is supplied to the primary winding of the transformer at 80 6,600 volts. With the type of synchronous converter at present customary, there are six very large collector rings, each of which with its equipment of brushes has to be designed to transmit about 5,000 amperes. In 85 our apparatus, these six enormous collector rings are replaced by three relatively small collector rings, which with their equipment of brushes will each have the duty of transmitting only about 300 amperes. Of course 90 these three small collector rings have to be designed and insulated for 6,600 volts, as against the relatively low voltage of the collector rings in the present day outfit. There thus becomes available practically all 95 the space now occupied by the six large collector rings. In our improved apparatus, the rotatable transformer can be mounted on the shaft of the synchronous converter in a space not much larger than that now 100 occupied by the six large collector rings.

Our improved arrangement, however, goes very much further than simply mounting a transformer in place of the collector rings of the present day outfit. It enables 105 us to readily employ twelve or more taps per pair of poles of the synchronous converter as against the six taps per pair of poles now usually employed. Indeed, there is no particular limit to the number of taps per pair 110 of poles which can be readily used when the transformer and armature windings rotate as a unit, and where any noteworthy economy is obtainable in going beyond twelve 115 taps per pair of poles, it can be conveniently done, as hereinbefore described, whereas in the case of the present day synchronous converter outfit, an increase of the number of collector rings has been considered by those skilled in the art as involving 120 125 130

such a radical departure that it took several years to introduce in practice six collector rings in place of three, after it had been widely recognized that such a change 5 would be associated with great advantages. A similar attitude has for years stood in the way of obtaining the further advantages which are associated with the use of twelve collector rings in place of six rings. By our 10 improved arrangement it may be said that we short-circuit all this delay, and obtain the advantages of twelve or more collector rings without the attendant disadvantages which have heretofore prevented the adoption 15 of more than six taps per pair of poles of the rotary converter.

It is well here to dwell a little more at length on the advantages of twelve collector rings, since the older theoretical disquisitions 20 were to the effect that nearly all the possible advantage was obtained in going from three to six collector rings, and that the further advantages, as regards electro-magnetic arrangements, in going from six to 25 twelve rings would only be of the order of 10 per cent., or thereabout. Formerly—those skilled in the art were not sufficiently conversant with the facts relating to the difference in heating at different parts of the 30 armature coils. The greatest heating is at the tap coils and the intermediate coils are very much less heated. The ratio of the heating in the hottest coils to the heating in the coolest coils is very high in a machine with three taps per pair of poles. It is 35 much lower in a machine with six taps per pair of poles, and it is still lower in a machine with twelve taps per pair of poles. Furthermore, as we increase the number of 40 taps per pair of poles we are able, by means of resort to a fractional pitch winding where the fractional pitch is not much less than the full pitch, to distribute the tap coils more uniformly among the slots. For example, 45 where we have twelve taps per pair of poles we can, in lighting rotaries, with a winding pitch of about 95 per cent., have in every slot a pair of coil sides, one of which is a tap coil and consequently would 50 ordinarily run at a high temperature and the other of which is a coil one-half way between taps and would ordinarily run at a low temperature. By simple expedients in the thermal design we can arrange for the 55 two coils and the magnetic core to so share one another's heat energy that the difference between the temperatures in the two coils will be relatively small as compared with present practice. It is obvious that the temperature 60 of the tap coils limits the rating of the machine, and in view of the foregoing explanation it will be clear that the increase in rating, due to the use of an increased number of taps per pair of poles, is greater than 65 would be deduced from the consideration of

the total armature I^2R losses. Furthermore, the more taps per pair of poles, the greater is the percentage of the total input to the synchronous converter which passes directly through the armature to the commutator 70 without involving any inefficient energy transformation. Consequently, a gradual increase in efficiency is attained by an increase in the number of taps per pair of poles. Furthermore, with such an increase in the number of taps per pair of poles what may be called the "local symmetry" is greater throughout the design. With three taps per pair of poles we can have a perfectly symmetrical design, when 75 considering the design as a whole, but we do not have the quality for which the term "local symmetry" has been employed above. This is obtained throughout the periphery of the armature to a much greater degree by 80 employing many taps per pair of poles. This improvement in the "local symmetry" will be associated with material improvement in commutation. The heating of a commutator is by no means due exclusively 85 to the friction and legitimate I^2R losses at the brush contacts, but is in considerable measure due also to the useless currents flowing during the period of commutation of each coil. We arrive much further toward the ideal of utterly eliminating these 90 commutation losses, which are not confined to the commutator but occur in all parts of the coil undergoing commutation as well as in the neighboring parts of the coil, when 95 we use a large number of taps per pair of poles. By taking intelligent advantage of all these gains, we are able, by the application of our present invention, to either improve the quality of a synchronous converter 100 for a given output, or else for a given quality to appreciably decrease the size and cost of the converter.

Two further advantages may in addition be obtained as a result of the improvement 110 in the commutation due to the use of an increased number of taps per pair of poles. In certain cases the improvement in the commutation is such that the interpoles, heretofore generally employed, may satisfactorily be dispensed with. This permits of slightly decreasing the pole pitch, which works in nicely with the decreased size of armature conductors, which becomes possible when the number of taps per pair of 115 poles is increased. Then too, the improvement in the commutation enables us to operate the rotary at higher speeds than has heretofore been considered practicable.

The design of the transformer in our improved apparatus adapts itself admirably to obtaining high reactance. Indeed, the design in actual practice has as high reactance as is desired for regulation of the commutator voltage by field control. This is in 120 125 130

striking contrast with the present day outfit, where in some cases, central stations actually pay more for transformers with high reactance, although the transformers in question have undesirable characteristics as regards stray losses and efficiency. Another advantage of our improved apparatus which should be particularly emphasized is that it has no moving contacts after the high pressure electricity has been conducted to the primary winding of the transformer until the low pressure direct current electricity is delivered at the commutator brushes. In other words, there are no moving contacts in the apparatus except those for connecting the apparatus directly to the high pressure system and the low pressure system.

A still further important advantage of our present apparatus is that the secondary winding of the transformer can be divided into a large number of independent circuits, thus decreasing the amount of current flowing in any secondary winding circuit. For low voltage synchronous converters of very large output, it is most desirable to get away from the very expensive heavy conductors which have been customary in the secondary winding circuits, and to employ instead many secondary circuits, each of a few turns of wire of fairly small cross section. Since in our improved apparatus the secondary winding conductors go direct from the transformer to the synchronous converter, the secondary winding can be divided into $(t.p)$ independent secondary circuits, each proportioned for a relatively small current, where t is the number of taps per pair of poles and p is the number of pairs of poles of the converter. In this manner we at once overcome one of the very greatest objectionable features of the ordinary stationary transformer for synchronous converters, namely, the heavy, unwieldy, and expensive secondary windings.

In all of the embodiments of our invention hereinbefore described, the primary and secondary windings of the transformer have rotated as a unit. The invention may, however, be very advantageously carried out by rotating only the secondary winding of the transformer and assembling the primary winding on a stationary core section, as described and claimed in the copending application of Henry M. Hobart, Ser. No. 121,504, filed September 21, 1916. Certain of the appended claims, therefore, cover this modification of the invention as well as those particularly described herein.

We have herein shown and particularly described certain embodiments of our invention for the purpose of explaining its principle and showing its applications, but numerous modifications in the details of construction and arrangements of these embodiments and other applications will pre-

sent themselves to those skilled in the art. We, therefore, wish to cover by the following claims all modifications within the spirit of the invention.

What we claim as new and desire to secure by Letters Patent of the United States, is:—

1. An electricity transforming and converting apparatus comprising a synchronous converter having a magnetic field system and an armature winding adapted to rotate therein, and a phase-multiplying transformer having a primary winding connected to slip rings and a secondary winding connected to said armature winding, said armature and transformer windings and said slip rings being carried by the rotatable element of said apparatus. 75

2. An electricity transforming and converting apparatus comprising a synchronous converter having a rotatable shaft, a magnetic core mounted on said shaft, an armature winding carried by said core, slip rings mounted on said shaft, and a phase-multiplying transformer carried by said shaft 90 and having primary and secondary windings electrically connected between said slip rings and said armature winding. 85

3. An electricity transforming and converting apparatus comprising a rotatable shaft, slip rings mounted on said shaft, a synchronous converter having a stationary magnetic field system and an armature winding carried by said shaft, and a phase-multiplying transformer carried by said shaft 100 and having primary and secondary windings one of which windings is connected to said slip rings while the other winding is connected to said armature winding. 95

4. An electricity transforming and converting apparatus comprising a synchronous converter having a stationary magnetic field system and a rotatable member carrying an armature winding so that the armature winding is adapted to rotate within said 110 magnetic field system, slip rings carried by said rotatable member, and a transformer having primary and secondary windings carried by said rotatable member, the primary winding of said transformer being arranged as a six phase winding electrically 115 connected to said slip rings, the secondary winding of said transformer being arranged to produce a greater number of phases than the primary winding and having its terminals electrically connected to appropriate 120 points of said armature winding. 120

5. An electricity transforming and converting apparatus comprising a rotatable member, a stationary magnetic field system, 125 an armature winding carried by said rotatable member and associated with said magnetic field system to form a synchronous converter, a transformer having primary and secondary windings carried by said ro- 130

- 5 tatable member, the secondary winding of said transformer being electrically connected to said armature winding, and a plurality of slip rings carried by said rotatable member and electrically connected to said primary winding, said primary winding being arranged to produce a greater number of phases than the number of said slip rings and said secondary winding being arranged 10 to produce a greater number of phases than said primary winding.
6. An electricity transforming and converting apparatus comprising a rotatable member, a stationary magnetic field system, an armature winding carried by said rotatable member and associated with said magnetic field system to form a synchronous converter, a transformer having primary and secondary windings carried by said rotatable member, the secondary winding of said transformer being electrically connected to said armature winding, and three slip rings carried by said rotatable member and electrically connected to said primary 20 winding, said primary winding having six coils three of which are star-connected with respect to each other while the other three are delta-connected with respect to each other thereby forming a six phase primary 25 winding, said secondary winding having a greater number of coils than said primary winding and arranged to produce a greater number of phases than said primary winding.
- 30 7. An electricity transforming and converting apparatus comprising a synchronous converter having a stationary magnetic field system and a rotatable member carrying a commutated armature winding, a phase-multiplying transformer arranged to rotate as a unit with said rotatable member, one of the windings of said transformer being electrically connected to said armature winding, and electric current collecting means 35 carried by said rotatable member and electrically connected to the other winding of said transformer.
8. An electricity transforming and converting apparatus for receiving high pressure polyphase alternating current electric energy and delivering relatively low pressure direct current electric energy comprising in combination a synchronous converter having a stationary magnetic field system and a commutated armature winding arranged to rotate within said system whereby conversion from alternating current energy to direct current energy is effected in said armature winding, a step-down phase-multiplying transformer arranged to rotate as a unit with said armature winding, the low pressure winding of said transformer being electrically connected to deliver low pressure alternating current energy to said armature 50 winding, and means for delivering high pressure alternating current energy to the high pressure winding of said transformer.
9. An electricity transforming and converting apparatus comprising a synchronous converter having a stationary magnetic field system and a rotatable member carrying a commutated armature winding, a step-down transformer arranged to rotate as a unit with said rotatable member, the low pressure winding of said transformer being electrically connected to said armature winding, and slip rings carried by said rotatable member and electrically connected to the high pressure winding of said transformer, the low pressure winding of said transformer being arranged to produce a greater number of phases than the high pressure winding thereof.
10. An electricity transforming and converting apparatus comprising a synchronous converter having a stationary magnetic field system and a rotatable member carrying a commutated armature winding, a step-down transformer arranged to rotate as a unit with said rotatable member, the low pressure winding of said transformer being electrically connected to said armature winding, and slip rings carried by said rotatable member and electrically connected to the high pressure winding of said transformer, the high pressure winding being arranged to produce a greater number of phases than the number of said slip rings and said low pressure winding being arranged to produce a greater number of phases than said high pressure winding.
11. An electricity transforming and converting apparatus comprising a dynamo-electric machine for receiving polyphase alternating current electric energy and delivering direct current electric energy, said dynamo-electric machine having a rotatable member carrying an armature winding, a phase-multiplying transformer arranged to rotate as a unit with said rotatable member, electric current collecting means carried by said rotatable member, and means electrically connecting one of the windings of said transformer between said electric current collecting means and said armature winding.
12. An electricity transforming and converting apparatus comprising a dynamo-electric machine for receiving polyphase alternating current electric energy and delivering direct current electric energy, said dynamo-electric machine having a rotatable shaft carrying a magnetic core and an armature winding, a second magnetic core secured to and carried by said shaft, phase-multiplying transformer windings arranged on said second magnetic core, and slip rings carried by said shaft, the high pressure winding of said transformer being electrically connected to said slip rings and

the low pressure winding of said transformer being electrically connected to said armature winding.

13. An electricity transforming and converting apparatus comprising a dynamo-electric machine for receiving polyphase alternating current electric energy and delivering direct current electric energy, said dynamo-electric machine having a rotatable shaft carrying a magnetic core and an armature winding, a second magnetic core secured to and carried by said shaft, said second magnetic core having two sections one of which is spoke-shaped and the other is annular and arranged around the outer periphery of the first section, primary and secondary transformer windings mounted on the spokes of said spoke-shaped core section, said secondary transformer windings being electrically connected to said armature winding, and slip rings carried by said rotatable shaft and electrically connected to said primary transformer windings.

14. An electricity transforming and converting apparatus comprising a synchronous converter having a stationary magnetic field system and a rotatable member carrying a commutated armature winding, a polyphase transformer arranged to rotate as a unit with said rotatable member, the secondary winding of said transformer being electrically connected to said armature winding at twelve or more places per pair of poles thereof, and slip rings carried by said rotatable member and electrically connected to the primary winding of said transformer.

15. An electricity transforming and converting apparatus comprising a dynamo-electric machine for receiving polyphase alternating current electric energy and delivering direct current electric energy, said dynamo-electric machine having a rotatable shaft carrying a magnetic core and an armature winding, a second magnetic core secured to and carried by said shaft, said second magnetic core having two sections one of which is spoke-shaped and the other is annular and arranged around the outer periphery of the first section, primary and

secondary transformer windings mounted on the spokes of said spoke-shaped core section, and slip rings carried by said rotatable shaft and electrically connected to said primary transformer windings, said primary transformer windings being arranged to produce a greater number of phases than the number of said slip rings and said secondary transformer windings being arranged to produce a greater number of phases than said primary transformer windings, said secondary transformer windings being electrically connected to said armature winding.

16. An electricity transforming and converting apparatus comprising a dynamo-electric machine for receiving polyphase alternating current electric energy and delivering direct current electric energy, said dynamo-electric machine having a rotatable shaft carrying a magnetic core and an armature winding, a second magnetic core secured to and carried by said shaft, said second magnetic core having two sections one of which is spoke-shaped and the other is annular and arranged around the outer periphery of the first section, primary and secondary transformer windings mounted on the spokes of said spoke-shaped core section, said primary transformer windings being connected to form two three phase windings of which one is star-connected and the other delta-connected whereby a six phase primary winding is obtained, and slip rings carried by said rotatable shaft and electrically connected to said primary transformer windings, said secondary transformer windings being electrically connected to said armature winding at a plurality of points per pair of poles of the armature winding, said secondary transformer windings being furthermore connected to produce a greater number of phases than said primary transformer windings.

In witness whereof we have hereunto set our hands this 5th day of September, 1916.

CHARLES W. STONE.
HENRY M. HOBART.
